UNITED STATES PATENT OFFICE.

MERVYN O'GORMAN, OF CHELSEA, LONDON, ENGLAND.

VIBRATO DEVICE FOR TALKING-MACHINES.

1,333,726.

Specification of Letters Patent. Patented Mar. 16, 1920.

Application filed January 4, 1917, Serial No. 140,621. Renewed January 29, 1920. Serial No. 354,882.

To all whom it may concern:

Be it known that I, MERVYN O'GORMAN, a subject of the King of Great Britain and Ireland, and residing at Chelsea, London, S. W., England, have invented a certain new and useful Vibrato Device for Talking-Machines, of which the following is a specification.

The present invention relates to gramophones, talking machines, phonographs and the like, and has for its object the introduction of a tremolo either when making the "record" in the first instance and the provision of means whereby the operator can during the actual course of reproduction of music, speech and other sounds, accentuate, modulate or give feeling or expression to the sound, at his own free will, thus rendering the reproduction less mechanical and monotonous.

In talking machines and the like, whether or not a tremolo has been introduced in the original formation of the record, when a record is sounded over and again in the ordinary manner, owing to each repetition being precisely similar to the last the result is much more monotonous than when the same piece of music, &c., is repeated by the human performers, partly owing to the variations made consciously or unconsciously by the performers.

The present invention consists in providing means for effecting at will a change in the relative positions of the reproducing point and the sound groove, (for example a slight oscillation such as a rapid advancing and retarding of the relative position of the reproducing point and the sound groove) while the reproduction is actually taking place. The introduction of such a fluctuating relative motion may be effected in any manner and various results accrue according to the speed and character of the fluctuations.

Thus, a movement of the point back and forth along the general direction of the sound groove at the rate of from about four to twenty per second produces a tremolo effect by reason of the perceptible variations of pitch, and these variations alter the timbre of the notes and moreover cause those notes which are sustained to attract the listener's attention and therefore to appear more accentuated. Generally speaking, the higher the notes and the quicker they are played, the more rapid the

fluctuating motion between point and record may be made to produce the tremolo, and on records such as are made at present an amplitude of motion of $\frac{1}{8}$ inch back and forth will suffice, but it may be exaggerated or diminished to produce special effects. Notably in spoken as distinct from intoned speech the amplitude may be much larger. For piano, unless a freak result is intended, it must be very small, much smaller than with violin or cornet.

In a general way an effect analogous to the organ stop known as "vox humana" may be introduced at will. At higher speeds of fluctuation the tremolo effect is less noticeable but the alteration of timbre remains up to a high speed, and it is found that this effect results in masking the scratching sound produced by friction between the stylus and the record to a very large extent, this being due to the fact that there is less frictional drag between the point and the rotating record.

The invention is alike applicable to talking and other records which employ the horizontal groove with double constraint of the point as in gramophones, or the vertical or phonograph groove with up and down sinusities to command the point.

The invention further consists in the means for varying the mechanical reproduction in talking machines and the like hereinafter described.

I illustrate one method of carrying into effect the introduction of the tremolo at will during reproduction of the sound by the accompanying drawings.

Figure 1 is a view partly in perspective and partly in section showing the invention. Fig. 2 shows a modification and Figs. 3 and 4 are details of a part of Fig. 1.

Figs. 1, 3 and 4 represent a talking machine or gramophone containing in the box *a* the usual mechanism to turn the record *b*. The tone arm *d* to which the sound from the sound box *c* is conveyed by the tube *e* communicates in the usual manner with the trumpet *b* by a swivel or universal joint or sleeve at *f*. The tube *e* is so disposed as to allow of relative movement between the sound box *c* and the tone arm *d*. This relative movement may be provided for by making the tube *e* of flexible material such as india rubber. The point *h* can be swayed to and fro in the direction of the sound groove either as shown by moving the sound box

bodily forward to the dotted position or by other means to be indicated later. In either of the present cases this is conveniently effected by the lever or wire *f* which is moved by an actuating lever *g*. The actuating lever *g* may be controlled by the finger for simplicity, but in a more convenient form the finger motion is replaced by connecting the actuating lever through a loose connection *m* to a vibrating table *t* of the ordinary kind, such as is vibrated by reason of carrying an out of balance fly wheel *n* or by contact with a cam or a vibrating spring, &c. When the loose connection *m* is tightened by the operator the vibrations of the vibrating table are imparted to the system of which the sound box forms part and causes the tremolo, and when the connection is once more loosened the tremolo ceases or diminishes.

In all cases I introduce a padded stop *x*, Fig. 1, against which the arm carrying the sound box is brought by a spring *s* or weight or by the drag of the moving record so that when the tremolo or vibrator is not in use there may be no unintentional changes of pitch. For the same reason I prefer to lower the hinge point on the lever *f*, Fig. 1, so as to be at the level of the needle point and thus avoid changes of pitch when a record happens to be warped or twisted as sometimes occurs.

Fig. 2 illustrates one method by which with a movable tone arm the additional freedom of movement for the sound box is provided. The hinged tube *e* fits into a socket communicating with the tone arm, and allows the wire or lever *f*, Fig. 2, when actuated by the finger or by the vibrating table to move the sound box.

Having now described my invention what I claim as new and desire to secure by Letters Patent is:—

1. In a talking machine, a record, having a sound groove, a sound box having a diaphragm, a point carried by the sound box and engaging the groove of the record, means for rotating the record to make the point traverse the groove and means for giving a relative back and forth movement to the record and point, additional to the regular traversing movement of the point, substantially as described.

2. In talking machines, a record, a sound groove on said record, a sound box, a point carried by said sound box and engaging with said groove, a diaphragm operated by said point, and means for rapidly oscillating said sound box with the point in the direction of rotation of the record, as set forth.

In testimony whereof, I have affixed my signature.

MERVYN O'GORMAN.
